UNITED STATES PATENT OFFICE

2,461,693

WRIST WATCH STRAP

Francis Richard McAloon, Waterbury, Conn., assignor to The United States Time Corporation, Middlebury, Conn., a corporation of Connecticut

Application January 29, 1947, Serial No. 725,050

7 Claims. (Cl. 24—265)

1

This invention relates in general to a wrist watch strap and particularly to a wrist watch strap which may be directly attached to a watch of ordinary construction without the use of any separate connecting means such as normally employed in connecting straps to wrist watches. It has been in the past, and is now, the almost universal practice of providing a device known as a spring bar for connecting straps to wrist watches. Such a spring bar consists of a tubular member having a pair of spring pressed pins protruding from the ends thereof, and in practice, this bar is placed through a loop provided therefor in the ends of the watch strap and the pins are then put under compression and placed between a pair of perforated ears provided therefor on the watch case and allowed to re-expand so that the pins are engaged within the perforations. Such spring bars are relatively expensive and are likewise difficult to insert.

It is an object of this invention to provide an arrangement whereby the ordinary spring bar commonly employed for fastening a strap to a wrist watch may be eliminated.

It is a further object of this invention to provide a wrist watch strap having as a unitary part thereof means for fastening said strap to a wrist watch of ordinary construction.

It is the specific object of this invention to provide a wrist watch strap so constructed that same may be quickly and easily connected to a wrist watch of ordinary construction and which will be inexpensive to manufacture.

These and further objects of the invention will more readily appear as the description thereof proceeds.

Referring now to the drawing wherein:

Fig. 1 is a front elevational view, partly in section, showing a wrist watch strap made in accordance with this invention connected to a wrist watch of ordinary construction;

Fig. 2 is a view similar to Fig. 1 showing another embodiment of this invention;

Fig. 3 is an enlarged detailed view, partly in section, showing the method of attaching a wrist watch strap made in accordance with this invention to a wrist watch;

Fig. 4 is a perspective view of a complete wrist watch strap made in accordance with this invention and showing one manner of attaching the free ends of the strap together; and

Fig. 5 is a detailed view, partly in section, showing the prior art.

Describing first briefly the prior art as shown in Fig. 5, a portion of a wrist watch case is indi-

cated at 2. Said case is provided with a pair of ears 4 and 6 and these ears are perforated as indicated at 8 and 10 respectively. Generally indicated at 12 in Fig. 5 is a spring bar of the usual construction, such bar consisting of a tubular sleeve member 14 having a coil spring 16 therein and having also a pair of pins 18 and 20 protruding from the ends thereof. A wrist watch strap is indicated in Fig. 5 at 22 and, as clearly indicated, the spring bar 12 extends through a loop provided therefor in the end of the strap. In assembling the strap and the watch case, the common practice is to place one of the pins, say 18, in the perforation 8 of the ear 4 and then press the pin 20 inwardly to a point where it may be fitted into the perforation 10 of the ear 6. Such an arrangement as this has attained almost universal adaptation in the trade even though these spring bars are obviously relatively expensive and even though it is often quite difficult to insert the two pins within the respective perforations provided therefor.

For a wrist watch strap made in accordance with this invention, reference is to be had first to Fig. 1 wherein the wrist watch case 2 referred to in the description of the prior art is seen in its entirety. Such case has a pair of ears 4 and 6 having perforations 8 and 10 respectively, protruding from either side thereof. One section of the wrist watch strap is indicated at 24 and the other at 26. Actually, this invention is equally adaptable to a strap of the type which is continuous and has each end attached to the wrist watch and to the type wherein the complete strap consists of two separate sections, one end of each section being attached to the wrist watch and the two then free ends being connected together by a buckle or other suitable connecting means. Since the ends of the strap, or of the two strap sections, are identical, only one of them will be referred to in detail.

A strap made in accordance with this invention may be made of numerous different materials, such as a synthetic resin of which certain co-polymers of vinyl chloride and vinyl acetate and certain polyamides are examples, leather, or even in some instances of metal. In Fig. 1, the section 24 of the strap has a pair of outwardly extending metal pins 28 and 30 protruding from the sides thereof and has a slot 32 extending longitudinally thereof and opening inwardly from the end thereof. It will readily be observed that this slot extends for such a distance as to lie between and separate the two pins 28 and 30. If the strap is molded of a synthetic resinous material, which

arrangement is contemplated by one embodiment of this invention, the pins 28 and 30 may be placed within the mold and the strap then molded around the pins so as to form a unitary structure of strap and pins. It will be noted that the pins are headed at their inner ends so as to give added resistance to pulling loose from the strap. If the strap is made of some other material such as leather, which is also contemplated by this invention, then it will be understood that the pins 28 and 30 will be sewed into the band.

Fig. 3 clearly shows the method by which the strap is connected to the watch case. The end of the strap adjacent the pins 28 and 30 is put under compression so as to close the open end of slot 32 and one of the pins, say 28, is positioned within the perforation 8 of the ear 4 and the other pin 30 is positioned in axial alignment with the perforation 10 of the ear 6. Then after the compressive force is removed from the end of the band, the slot 32 will open up due to the resiliency of the material of which the band is made and the pin 30 will move into the perforation 10, thereby securely connecting the strap to the watch. It will be understood that the expanded width of the strap is substantially equal to the distance between the spaced ears 4 and 6 and that the slot 32 is of such a width that when its open end is closed, the distance between the outer ends of the pins will be such that the pins will fit between the ears of the watch case as pointed out above.

Another embodiment of the invention is illustrated in Fig. 2 wherein parts similar to those referred to above are given the same reference numeral for ease of understanding. In this embodiment of the invention, the metallic pins 28 and 30 are formed on the ends of a generally U-shaped resilient member 34. The section 24 of the strap may be molded around the U-shaped member 34 so as to form a unitary structure therewith if the strap is molded of a synthetic resinous material or, as pointed out in connection with Fig. 1, the U-shaped member 34 may be sewed within the strap if said strap is made of leather or other similar material. This structure has the advantage over the Fig. 1 construction of added strength and also of assuring that the slot 32 will expand to its original size after same has been closed while attaching the band to the watch. It will, of course, be obvious that this band is attached to the watch in a manner identical with that described above in relation to the Fig. 1 construction.

The perforations 8 and 10 in the ears 4 and 6 are usually of a very small diameter, but if it should be desirable to make said perforations of a larger diameter, then it is within the scope of this invention to integrally mold the strap and the pins so that the pins are likewise formed of a synthetic resinous material rather than of metal, as is the case in the previously described embodiments of the invention. Unless the diameter of the perforations in the ears is increased, the pins, if formed of a synthetic resinous material, would

likely not be strong enough to securely hold the band to the watch.

While the invention has been illustrated and described in its preferred embodiments and has included certain details, it should be understood that the invention is not to be limited to the precise details herein illustrated and described since the same may be carried out in other ways, falling within the scope of the invention as claimed.

10. What I claim is:

1. A wrist watch strap comprising a flexible member having a pair of outwardly extending pins adjacent one end thereof and having a longitudinally extending slot in the end thereof between said outwardly extending pins.

2. A wrist watch strap comprising a flexible member formed of a synthetic resinous material and having a pair of outwardly extending pins adjacent one end thereof and integral therewith and having a longitudinally extending slot in the end thereof between said outwardly extending pins.

3. A wrist watch strap comprising a flexible member having a pair of outwardly extending metallic pins adjacent one end thereof and having a longitudinally extending slot in the end thereof between said outwardly extending pins.

4. A wrist watch strap comprising a flexible member molded of a synthetic resinous material and having a pair of outwardly extending metallic pins adjacent one end thereof and integrally molded therewith and having a longitudinally extending slot in the end thereof between said outwardly extending pins.

35. 5. A wrist watch strap comprising a flexible member molded of a synthetic resinous material and having a pair of outwardly extending pins adjacent one end thereof, said pins also being molded of a synthetic resinous material and integral with said flexible member, said flexible member having a longitudinally extending slot in the end thereof between said outwardly extending pins.

45. 6. A wrist watch strap comprising a flexible member, a generally U-shaped member carried by said flexible member and providing at its extremities a pair of outwardly extending pins located adjacent one end of said flexible member, a longitudinally extending slot in the end of said flexible member, said slot being positioned between said outwardly extending pins.

55. 7. A wrist watch strap comprising a flexible member molded of a synthetic resinous material, a generally U-shaped member integrally molded into said flexible member and providing at its extremities a pair of outwardly extending pins located adjacent one end of said flexible member, a longitudinally extending slot in the end of said flexible member, said slot being positioned between said outwardly extending pins.
